UNITED STATES PATENT OFFICE.

JACOB O. PARRISH, OF POMONA, CALIFORNIA.

SPRING-EYE BENDER.

Application filed August 11, 1924. Serial No. 731,444.

This invention relates to benders and consists of the novel features herein shown, described and claimed.

An object is to make a machine especially adapted for bending eyes on springs and adapted for making any desired round or angular bend on the end of a flat bar.

Other objects and advantages will appear from the drawings and specification.

10 The drawings illustrate the construction and operation of the invention.

Fig. 1 is a perspective of the bender, the parts being disassembled ready to receive an article to be bent.

15 Fig. 2 is a view analogous to Fig. 1 and showing a flat bar such as a leaf-spring in place ready to be operated upon.

Fig. 3 is a sectional elevation with the parts in place and a bend partly made.

20 Fig. 4 is a vertical cross-section on the line 4—4 of Fig. 3 and looking in the direction indicated by the arrows.

Fig. 5 is a fragmentary perspective showing the end of a spring with a round eye as made in my machine.

Fig. 6 is a fragmentary diagrammatic view showing how a right angled bend may be made.

30 Fig. 7 is a fragmentary perspective of a right angled bend made as shown in Fig. 6.

The details of construction and operation shown in the drawings are as follows:

The bender bed 1 is a piece of heavy channel iron turned flat side up and mounted on a strong bench 2 with the operating end extending from the bench.

35 Guide posts 3, 4, 5 and 6 have their lower ends bent at right angles so as to fit upon the bench 2 against the sides of the bed 1 and extend upwardly from the bed 1.

The posts are secured to the sides of the bed 1 by rivets 7 and are secured to the bench 2 by bolts 8.

40 A bearing plate 9 fits across the bottom of the bed 1 just in front of the bench 2 and may be welded to the side flanges of the bed 1.

An eccentric 10 fits against the bearing plate 9 and a U-shaped plate 11 fits the eccentric and has side flanges 12 and 13 connected to the plate 9 by bolts 14 and 15.

Bearing bars 16 and 17 fit against the sides of the bed 1 and against the ends of the eccentric 10, and the rear ends of the bars 16 and 17 have transversely alined slots 18, and

a pivot bolt 19 extends through the bed 1 and loosely through the slots 18. Bearing plates 20 and 21 fit against the outsides of the bars 16 and 17 and are rigidly held in place by rivets 22. The bearing plates 20 and 21 extend below the bars 16 and 17 and have bearings in which the pintles 23 and 24 of the eccentric 10 are mounted. A handle 25 is fixed upon the pintle 23 for operating the eccentric 10. Bearing heads 26 and 27 are formed upon the forward ends of the bars 16 and 17 and have large heart-shaped bearing openings 28 and 29 in transverse alinement with the points of the openings extending upwardly.

The bar 30 to be bent fits upon the bed 1 and projects forwardly a slight distance from the forward end of the bed. The eccentric handle 25 is operated to raise the heads 26 and 27 and the mandrel 31 is inserted through the openings 28 and 29 over the bar 30 and the handle 25 again operated to lower the heads 26 and 27 and hold the mandrel 31 and the points of the openings 28 and 29 serve to accurately center the mandrel and bring it into the same position at each operation.

The heads 26 and 27 are spaced from the sides of the bed 1. The bending lever heads 32 and 33 have heart-shaped openings 34 and 35 with centering points 36 and 37 in transverse alinement and the heads 32 and 33 fit against the sides of the bed 1 inside of the heads 26 and 27 with the mandrel 31 engaging in the points 36 and 37 of the openings. Arms 38 and 39 extend from the heads 32 and 33 and a cross bar 40 extends loosely through the arms 38 and 39. A tongue 41 is welded to the cross bar 40 at its center and is slidingly mounted through a bearing 42. The bending member 43 extends from the bearing 42 over the cross bar 40 between the arms 38 and 39 and between the heads 32 and 33 and has a straight operating edge 44 parallel with the mandrel 31. A pipe 45 extends outwardly from the bearing 42 and a handle 46 has a head 47 rotatably engaging the outer end of the pipe 45 and the tongue 41 extends through the pipe 45 and is screwed into the head 47. The bore 48 through the head 47 and into the handle 46 is of considerable length and the thread upon the tongue 41 is of considerable length.

so that by rotating the handle 46 the tongue 41 is screwed in or out in the bore 48, thereby adjusting the position of the straight edge 44 relative to the mandrel 31 as required to bend a larger or smaller eye on the bar 30.

Normally the mandrel 31 is out of position, the bending lever is disconnected, and the heads 26 and 27 are elevated as shown in Fig. 1. Then the bar 30 is placed in position upon the bed 1, a proper mandrel 31 is selected and placed across the end of the bar 30, the bending lever is brought into position inside of the heads 26 and 27 and the mandrel 31 inserted through the heads 26 and 27 and 32 and 33 with the handle 46 hanging downwardly, the lever 25 is operated to tighten the mandrel against the bar 30, and the handle 46 is swung forwardly and upwardly in the direction indicated by the arrow 49 and the edge 44 engages under the end of the bar 30 and bends the bar upwardly and around the mandrel 31 as shown in Fig. 3, thereby producing the round eye 50 upon the bar 30, as shown in Fig. 5. Then the handle 46 is swung backwardly to its depending position, the handle 25 operated to release the mandrel 31, and the mandrel 31 is removed from the eye 50, and then the bar 30 carrying the eye 50 is removed from the bed 1.

The parts 32 to 48 constitute the bending lever 51. When the parts of the bending lever have been properly fitted and adjusted for a certain size mandrel it only requires a slight adjustment to fit a larger or smaller mandrel. The posts 3, 4, 5 and 6 are intended to serve as guides to hold long bars straight upon the bed 1.

In the process of making right angled bends as shown in Fig. 6, a square block 52 may be placed upon the mandrel 31 and the bender lever may have a right angled foot 53 to engage the bar 54 and press the end of the bar upwardly against the block 52 and make a square bend 55, as shown in Fig. 7. Of course, the angles and adjustments may be varied to suit different kinds of work.

The pintle 24 extends some distance through the bearing plate 21 and is squared. A segmental pawl rack 56 is mounted upon the squared end of the pintle 24 and held in place by a cotter 57. A pawl 58 is pivotally mounted upon the pivot bolt 19 and engages the rack 56. A weighted handle 59 extends forwardly and upwardly from the pawl 58 and is adapted to press the pawl 58 against the pawl rack 56 and is adapted to serve as a handle to raise the pawl out of engagement with the rack. The pawl and rack serve to hold the eccentric 10 in its adjusted position to grip and hold the mandrel 31 while the bending operation is being done.

Various changes may be made without departing from the spirit of the invention as claimed.

I claim:

1. A bender comprising a bed, bars pivotally mounted against the sides of the bed and having heads with alined mandrel openings at the free ends of the bars, an eccentric for operating the bars, a bender lever having mandrel openings, and a mandrel loosely inserted across the bed through the openings of the lever and bars, the lever having a working edge concentric to the mandrel. 70

2. A bender comprising a bed, bars pivotally mounted against the sides of the bed and having heads with alined mandrel openings at the free ends of the bars and near one end of the bed, an eccentric mounted under the bed for operating the bars, a bender lever having heads with mandrel openings fitting inside of the first heads, the mandrel openings being heart-shaped with their points upwardly, and a mandrel loosely inserted across the bed through the openings of the lever and bars, the lever having a working edge concentric to the mandrel. 80 85 90

3. A bender comprising a bed, bars pivotally mounted against the sides of the bed and having heads with alined mandrel openings at the free ends of the bars and near one end of the bed, an eccentric mounted under the bed for operating the bars, a bender lever having heads with mandrel openings fitting inside of the first heads, the mandrel openings being heart-shaped with their points upwardly, and a mandrel loosely inserted across the bed through the openings of the lever and bars, the lever having an adjustable working edge concentric to the mandrel. 95 100 105

4. In a bender, a bed adapted to be rigidly mounted and adapted to receive the article to be bent, bars pivotally mounted against the sides of the bed and having heads with large alined mandrel openings at one end of the bed and at the free ends of the bars, bearings extending downwardly from the bars, an eccentric mounted under the bed and having pintles extending into the bearings, and a lever for operating the eccentric. 110 115

5. A bender comprising a bed, bars pivotally mounted against the sides of the bed and having heads with alined mandrel openings at the free ends of the bars, an eccentric for operating the bars, a pawl and rack for holding the eccentric, a bender lever having mandrel openings, and a mandrel loosely inserted across the bed through the openings of the lever and bars, the lever having a working edge concentric to the mandrel. 120 125

6. A device of the class described comprising a bed, a mandrel, bars pivotally 130

mounted upon the bed having heads adapted to press the mandrel toward the bed, an eccentric rotatably mounted upon the bed adapted upon rotation to raise or lower the 5 bars, means for rotating the eccentric, and means for bending an article positioned on the bed beneath the mandrel about the mandrel.

7. A device of the class described comprising a bed, a mandrel, bars pivotally mounted upon the bed having heads adapted to press the mandrel toward the bed, an eccentric rotatably mounted upon the bed upon the under side thereof between the pivotal connection of the bars and the heads thereon, said eccentric being operatively connected to the bars so that upon rotation of the eccentric the bars may be forced toward or away from the bed, means for rotating the eccentric, and means for bending an article placed between the bed and the mandrel about the mandrel.

8. A device of the class described comprising a bed, a mandrel, bars pivotally mounted upon the bed having heads adapted to press the mandrel toward the bed, an eccentric rotatably mounted upon the bed upon the under side thereof between the pivotal connection of the bars and the heads thereon, said eccentric being operatively connected to the bars so that upon rotation of the eccentric the bars may be forced toward or away from the bed, means for rotating the eccentric, means for bending an 35 article placed between the bed and the mandrel about the mandrel, and a ratchet mech-

anism for holding the eccentric in that position in which the bars are tightly holding the mandrel against the article.

9. A device of the class described comprising a bed, a mandrel, means for clamping a mandrel against an article upon the bed, a bender lever having arms which pivot upon the mandrel for bending the article, said bender lever having a tongue pivoted 40 upon said arms, means movable upon the tongue carrying a bending member adapted to engage the article, and a handle threaded onto the tongue engageable upon said means whereby upon rotation of the handle the 45 bender member may be moved toward the mandrel and upon swinging the bender lever the article may be bent around the mandrel.

10. A device of the class described comprising a bed, a mandrel, means for clamping a mandrel against an article upon the bed, a bender lever having arms which pivot 50 upon the mandrel, a tongue carried by the arms, a sleeve disposed about the tongue and movable thereon and carrying a bending member adapted to engage the article, and a handle threaded onto the tongue engageable upon said sleeve whereby upon rotation of the handle the bender member mounted on the sleeve may be moved to- 55 ward the mandrel and upon swinging the bender lever the article may be bent around the mandrel.

In testimony whereof I have signed my name to this specification.

J. O. PARRISH.
